UNITED STATES PATENT OFFICE

93,278

DESIGN FOR A HAND MIRROR OR THE LIKE

Cecil H. Lawrence, Attleboro, Mass., assignor to Evans Case Company, North Attleboro, Mass.,
a corporation of Massachusetts

Application July 30, 1934, Serial No. 52,751

Term of patent 7 years

To all whom it may concern:

Be it known that I, CECIL H. LAWRENCE, a citizen of the United States, residing at Attleboro, county of Bristol, and State of Massachusetts, have invented a new, original, and ornamental Design for Hand Mirrors or the like, of which the following is a specification, reference being had to the accompanying drawing forming a part hereof.

I claim:

The ornamental design for a hand mirror or the like as shown.

CECIL H. LAWRENCE.
